ATTORNEY.

UNITED STATES PATENT OFFICE.

PAUL C. MURPHY, OF SEATTLE, WASHINGTON.

TELEPHONE-DIRECTORY.

No. 802,654.

Specification of Letters Patent.

Patented Oct. 24, 1905.

Application filed November 8, 1904. Serial No. 231,857.

To all whom it may concern:

Be it known that I, PAUL C. MURPHY, a citizen of the United States, residing at Seattle, in the county of King and State of Washington, 5 have invented certain new and useful Improvements in Telephone-Directories, of which the following is a specification, reference being had therein to the accompanying drawings.

The object of this invention is to provide a 10 case adapted to be conveniently attached to the transmitter-arm of a telephone for the purpose of providing a receptacle for a plurality of index or directory cards which would be alphabetically marked and arranged and upon 15 which can be written or otherwise marked with the names and telephone-numbers of subscribers with whom one has frequent or even occasional intercourse, thus obviating the necessity of repeatedly looking through the customary directory-lists, which is a very tedious 20 and aggravating undertaking.

The invention consists of the novel construction and combination of parts, as will be hereinafter described and illustrated in the accompanying drawings, wherein—

Figure 1 is a front elevation of the invention shown attached to a telephone-transmitter. Fig. 2 is vertical cross-section of the same, and Fig. 3 is a perspective view of a 30 detached directory-card.

In the drawings, the letter A represents a card-case comprised of side walls α , having inclined top edges, front and back walls α' and α'' , which coincide with the height of the said 35 sides thereat, and a bottom wall α'' . Provided in the respective back and front walls and in horizontal and axial alinement with each other are circular apertures b and b' of diameters corresponding, respectively, with the diameters 40 of the telephone-mouthpiece T adjacent of the screwed socket end t thereof and at a distance outwardly therefrom equal to the horizontal thickness of the case, and when this mouthpiece is screwed into the socket of the 45 diaphragm-chamber t' and by reason of its tapering form it will press the case firmly against said chamber. Projecting upwardly through an aperture d in the middle of the case-bottom is a thumb-screw e , which passes through a 50 screw-threaded registering aperture f of a non-rotatable plate g , so that as the screw is turned in one direction to impinge at its point against the under side of said mouthpiece it will exert a downward pressure upon the case

and hold the same rigidly in an upright position. 55

Alphabetically-indexed cards C are provided for the case and are severally formed with an incision c in their lower edges sufficiently large to permit the lower legs c' thereof loosely straddling the mouthpiece between the case-walls. These cards are preferably formed of two or more different heights in order that the denominating or initial letters of each may be seen at a glance without the need 60 of fingering or bending forward the cards in selecting the proper one. In manufacturing these cards, however, they are each desirably given a transverse crease to weaken them thereat and which creases arranged so that 65 the crease of any particular card will be somewhat higher than that of the card immediately in front of the same, as indicated by the line x in Fig. 2. The object of thus weakening the cards in an inclined plane is to enable 70 those in front of a selected one being bent forward sufficiently to display the names and telephone-numbers marked upon the latter without first removing it or the cards in front 75 from the case. 80

It is obvious from the foregoing that the invention is one of great utility. It is of simple and inexpensive construction and can be readily applied to any telephone where it is always in position for use. 85

Having described my invention, what I claim as new, and desire to secure by Letters Patent, is—

1. As a new article of manufacture, a directory-case for a telephone, comprising a box-like receptacle for holding a plurality of index-cards, said case being provided in its front and back walls with apertures adapted to receive the mouthpiece of a telephone, and a screw device for retaining said case in an upright position, substantially as described. 90

2. As a new article of manufacture, a card-case consisting of side walls, a bottom wall, a front wall and a rear wall of greater height than said front wall, said two last-named walls 100 being provided with telephone-mouthpiece-receiving apertures in axial alinement with each other, a thumb-screw extending upwardly through said bottom wall and passing through a screw-threaded aperture of a non-rotatable 105 plate positioned within the case, and the said plate, substantially as described.

3. In a device of the class described, in com-

bination with a case adapted to be held on and to the mouthpiece of a telephone, a plurality of indexed cards adapted to be held in said case, each card being creased along an approximately central line.

4. A device of the class described, in combination with a case adapted to be attached to the mouthpiece of a telephone, a plurality of indexed cards, adapted to be held in said case, each card being creased transversely between its upper and lower edges.

5. In a device of the class described in combination with a case adapted to be attached to the mouthpiece of a telephone, a plurality of indexed cards adapted to be held in said case and provided with transverse creases severally arranged at different heights.

6. In a device of the class described, in combination with a case adapted to be held on and to the mouthpiece of a telephone and means for securing the same to said mouthpiece, a plurality of indexed cards adapted to be held in said case and provided with transverse creases severally arranged at successively-increasing heights.

7. In a device of the class described, a case adapted to be held on and to the mouthpiece of a telephone, and a plurality of indexed cards adapted to be held in said case and provided with bifurcated ends, loosely straddling said mouthpiece, in combination with means for securing the case to said mouthpiece.

8. In a device of the class described, a card-case consisting of side walls, a bottom wall, a front wall and a rear wall of greater height than said front wall, said two last-named walls being provided with telephone-mouthpiece-

receiving apertures in axial alinement with each other, said case being capable of holding a plurality of indexed cards, formed with bifurcated ends, loosely straddling said mouthpiece and provided with transverse creases, severally arranged at successively-increasing heights, in combination with means for securing the case to said mouthpiece, said means embodying a thumb-screw extending upwardly through said bottom wall and passing through a screw-threaded aperture, of a non-rotatable plate positioned within the case and the said plate, substantially as described.

9. In a device of the type set forth in combination with a case adapted to be attached to the mouthpiece of a telephone and provided with an open end, a plurality of indexed cards adapted to be held in said case, each card being creased along a line parallel with the edges of the walls of said case adjacent to said open end.

10. In a device of the type described, in combination with a case adapted to be attached to the mouthpiece of a telephone, and provided with an open end, a plurality of indexed cards adapted to be held in said case and provided with transverse creases, severally arranged at successively-increasing distances, along lines parallel with the edges of the walls of said case adjacent to said open end.

In testimony whereof I affix my signature in presence of two witnesses.

PAUL C. MURPHY.
